Samuel Stohr,
Inventor
By my Esq. Edw. Seymour

UNITED STATES PATENT OFFICE.

SAMUEL STOHR, OF MERIDEN, CONNECTICUT, ASSIGNOR TO WILCOX & EVERTSEN, OF SAME PLACE.

DESIGN FOR A HANDLE FOR SPOONS, FORKS, &c.

SPECIFICATION forming part of Design No. 30,391, dated March 28, 1899.

Application filed March 1, 1899. Serial No. 707,406. Term of patent 3½ years.

To all whom it may concern:

Be it known that I, SAMUEL STOHR, of Meriden, in the county of New Haven and State of Connecticut, have invented and produced 5 a new Design for a Handle for Spoons, Forks, and Similar Articles; and I do hereby declare the following, when taken in connection with the accompanying drawings and the letters of reference marked thereon, to be a full, clear, 10 and exact description of the same, and which said drawings constitute part of this specification, and represent, in—

Figure 1, a face view of a spoon or fork handle embodying my design; Fig. 2, a reverse 15 view thereof.

My invention relates to a design for a handle for spoons, forks, and similar articles; and it consists in the configuration and ornamentation shown in the accompanying illustration and hereinafter described.

As herein shown, the design consists of a heavy bead-like border A, applied to the edges of the end of a spoon or fork handle of the so-called "fiddle pattern," the inner and outer 25 edges of the border being outlined by narrow

beads B. At their inturned outer ends the beads B terminate in scrolls C, separated by a crown-like trefoil D. The inner ends of the scrolls A may be said to rest upon the outer ends of scrolls E, which form the terminations 30 of two long beads E', which outline the stem of the handle and terminate at their inner ends in partial scroll-like and partial shell-like ornaments F, which merge into the spoon or fork. The ornamentation on the reverse 35 or end side of the handle is of the same character, although less enriched with scroll-like motives.

I claim—

The design for a handle for spoons, forks 40 and similar articles, as herein shown and described.

In testimony whereof I have signed this specification in the presence of two subscribing witnesses.

SAMUEL STOHR.
